UNITED STATES PATENT OFFICE

121,786

DESIGN FOR A CONTINUOUS ROTARY
DRUM FILTER

Edward D. Flynn, Oakland, Calif., assignor to
Oliver United Filters Incorporated, Oakland,
Calif., a corporation of Nevada

Application October 16, 1939, Serial No. 87,688

Term of patent 14 years

To all whom it may concern:

Be it known that I, Edward D. Flynn, a citizen of the United States of America and a resident of the city of Oakland, county of Alameda, State of California, have invented a new, original, and ornamental Design for Continuous Rotary Drum Filters of which the following is a specification, reference being had to the accompanying drawing, forming part thereof.

Figure 1 is a perspective view of one end and side of a continuous rotary drum filter showing my new design.

Figure 2 is a perspective view of the opposite end and side of the filter shown in Figure 1.

I claim:

The ornamental design for a continuous rotary drum filter, as shown.

EDWARD D. FLYNN.
